US00D958839S

(12) **United States Design Patent** (10) **Patent No.:** **US D958,839 S**
Dralle et al. (45) **Date of Patent:** **** Jul. 26, 2022**

(54) **PANEL FOR INTAKE MANIFOLD**

(71) Applicant: **Holley Performance Products, Inc.**,
Bowling Green, KY (US)

(72) Inventors: **James D. Dralle**, Bowling Green, KY
(US); **Corey D. Spainhoward**, Bowling
Green, KY (US)

(73) Assignee: **Holley Performance Products, Inc.**,
Bowling Green, KY (US)

(**) Term: **15 Years**

(21) Appl. No.: **29/713,627**

(22) Filed: **Nov. 18, 2019**

(51) LOC (13) Cl. **15-01**

(52) U.S. Cl.

USPC **D15/5**

(58) **Field of Classification Search**

USPC D15/1, 2, 3, 4, 5, 6

CPC F02M 35/104; F02M 35/108; F02M
35/1085; F02M 35/116

See application file for complete search history.

(57) **CLAIM**

The ornamental design of a panel for intake manifold, as
shown and described.

DESCRIPTION

Cross-reference is made to U.S. Design patent application Ser. No. 29/713,625, titled "Manifold," U.S. Design patent application Ser. No. 29/713,626, titled "Manifold," U.S. Design patent application Ser. No. 29/713,628, titled "Throttle Body Adapter," all filed on the same day as the present application and all of which are expressly incorporated herein by reference.

FIG. 1 is an upper perspective view of a design of a panel for intake manifold;

FIG. 2 is a front view of the design of FIG. 1;

FIG. 3 is a rear view of the design of FIG. 1;

FIG. 4 is a first side view of the design of FIG. 1;

FIG. 5 is a second side view of the design of FIG. 1;

FIG. 6 is a top view of the design of FIG. 1;

FIG. 7 is a bottom view of the design of FIG. 1; and,

FIG. 8 is a lower perspective view of the design of FIG. 1. The broken lines shown in the drawings are included for the purpose of illustrating the unclaimed boundary and/or unclaimed portions of a panel for intake manifold. The broken lines form no part of the claimed design.

1 Claim, 8 Drawing Sheets
